UNITED STATES PATENT OFFICE.

GEORGE HENRY CLARK, OF ALLSTON, MASSACHUSETTS, ASSIGNOR TO THE UTICA TREEING MACHINE COMPANY, OF BOSTON, MASSACHUSETTS, A CORPORATION OF MASSACHUSETTS.

SHOE-FINISHING JACK.

No. 892,224.

Specification of Letters Patent.

Patented June 30, 1908.

Application filed October 22, 1906. Serial No. 339,986.

To all whom it may concern:

Be it known that I, GEORGE HENRY CLARK, a citizen of the United States, residing at Allston, in the county of Suffolk and State of Massachusetts, have invented certain new and useful Improvements in Shoe-Finishing Jacks; and I do hereby declare the following to be a full, clear, and exact description of the invention, such as will enable others skilled in the art to which it appertains to make and use the same.

The present invention relates to a shoe finishing jack and more particularly to certain improvements in the jack and the last or follower whereby the application of the shoe thereto and its removal therefrom shall be facilitated, and to provide an improved connection between the last or follower and the jack whereby the last or follower and the shoe thereon will be securely held upon the jack during the manipulation of the shoe finishing tools in ironing and smoothing the upper of the shoe; and also to provide means which while acting to engage and fixedly hold the shoe in position, will at the same time extend the counter thereof at the back of the shoe, causing the counter of the shoe to be narrowed or drawn inward along the sides, thus producing the desired shape.

Further objects of the invention will appear in connection with the following description of its construction and arrangement.

To the above ends the present invention consists of the improved jack for finishing shoes which will be hereinafter described and claimed.

Figure 1 shows the device in side elevation, with portions thereof illustrated in dotted lines. Fig. 2 shows a rear elevation. Fig. 3 shows a vertical section taken upon the line 3—3, with the shoe in position upon the jack, and Fig. 4 shows the split jack pin removed from the device.

Similar reference characters will be employed throughout the specification and drawing to designate corresponding parts.

My improved jack 1 is preferably cast in a single integral piece and preferably of some light metal, such as aluminum, and at its lower end it may be provided with a substantially cylindrical shank 2, having a bore 3, whereby it may be mounted upon any convenient holder or spindle, as is usual in such devices.

The jack 1 comprises the leg and ankle portion of the device and at its upper end is provided with the inclined face 4. As shown in Figs. 1 and 2, the jack 1 is very much wider than it is thick, and its front and rear edge portions will be slightly rounded and formed upon the generally converging lines 5 and 6, which towards their upper ends diverge as shown at 7 and 8.

Projecting from the upper end of the inclined face 4 is a jack pin 9, which as shown in Figs. 1 and 2, will be inclined slightly towards the back of the device. This jack pin, as shown clearly in Fig. 4, is provided with a vertical slot 10, thus providing two yielding members 11 and 12, preferably having rounded ends 13. By thus constructing the pin, it may be readily inserted in the bore of the last or follower, which can be made of slightly less diameter than the diameter of the pin, thus causing the members 11 and 12 to frictionally engage the wall of the bore. The jack 1 is provided with a longitudinal slot or recess 14 entering from the back thereof and projecting inward towards the front as shown in Fig. 3, and as indicated by the dotted lines 15 in Fig. 1. Within this recess 14 is pivoted a bent lever 16 mounted upon a pivot 17 and extending in both directions above and below said pivot. The lower arm 18 of the lever 16 is arranged to be engaged by the cam shaped end 19 of a lever fulcrumed within the slot 14, upon a pin 20 and provided with a handle 21, whereby said lever may be rocked about its pivot 20 to cause the end 19 to engage the end 18 of the lever 16, thus moving said end 18 inward and causing a corresponding outward movement of the end 22 of the lever 16. The end 22 of the lever 16 extends upward above the inclined face 4 of the jack 1, as shown at 23, for a purpose which will be hereinafter described.

To rock the lever 16 in a reverse direction to that imparted by the lever 19, there is provided a coiled spring 24 which is seated within a bearing 25 against an adjusting screw 25^a, which spring at its inner end bears against the arm 18 of the lever 16 below the fulcrum 17. The last or follower 25 is provided with the bore 26 to receive the split pin 9 and at its rear end it is provided with a slot 27 extending vertically through the rear end of the last or follower back of the bore 26 and passing through both the bot-

tom and the top of the follower, as clearly indicated in Figs. 1 and 3. Within this recess 27 the upper end 23 of the lever 16 is arranged to fit and to move freely back and forth therein, and as shown in Fig. 2, the width of the slots 14 and 27 is substantially the thickness of the lever 16; and thus when the end 23 is fitted in the slot 27 of the last or follower it, in effect, performs the function 10 of a second jack pin holding and preventing the turning of the last or follower on the pin 9, and maintaining it in proper position on the jack.

As clearly indicated in Figs. 1 and 3, the 15 upper end 23 of the lever 16 is arranged to be projected from a position within the margin of the back of the last or follower 25 to a position outside of the margin, as shown in Fig. 3, and when rocked to this position 20 by the upturning of the handle 21 and the engagement of the cam end 19 with the end 18 of the rocking lever 16, the upper end 23 of this lever will forcibly engage the counter of the boot or shoe about at its longitudinal 25 vertical central portion and the shoe will be forced rearwardly at this point, thus causing the sides of the counter to be contracted and to closely engage the beveled sides 28 of the last or follower 25. While thus held, the 30 shoe may be ironed, rubbed, dressed, smoothed and otherwise finished as is common in the finishing of boots and shoes.

To facilitate the easy application of the shoe to the last or follower and its easy removal therefrom, the said last or follower at 35 its heel portion is cut away on an incline as indicated at 29, and thus the shoe may be drawn readily over and fitted to the last or follower.

40 It is well known that the tops of some shoes are cut fuller and wider than the tops of other shoes, and therefore it is desirable to adjust the width of the jack 1 at the point where the top of the high shoe engages the 45 same, and for this purpose there is fitted in the slot 14 an extension plate or slide 30, which is pivotally mounted at 31 so as to swing in and out, as shown clearly in Figs. 1 and 3. This plate 30 is provided with a 50 slot, through which is fitted an adjusting or clamping screw 32 provided upon the outside of the jack 1 with a winged head 33 whereby it may be turned to set the plate 30 in its

adjusted position either to hold the same wholly within the boundary of the jack 1, as 55 illustrated in Fig. 1, or to cause its rear edge to project beyond the rear edge 6 of the jack 1, as shown in Fig. 3 of the drawing.

The plate 30 will preferably be provided with means whereby it may be drawn from 60 the slot 14, and this may consist of the ring 34, which when the plate is retracted as shown in Fig. 1, is received in notches or recesses 35, cut in the rear edge 6 of the jack 1.

It is thought that the operation of my invention will be clear to those skilled in the art from the foregoing description and that further description is unnecessary.

Having described my invention I claim as new and desire to secure by Letters Patent 70 of the United States:

1. A shoe finishing jack comprising a leg portion and a removable foot portion, the foot portion having at the heel end a vertical slot, and the leg portion provided with a pivoted lever, said lever engaging both said leg and said foot portions on both sides of said lever and adapted to engage at its upper end the heel of the shoe to stretch the same rearwardly, and operating devices for said lever, 80 substantially as described.

2. A shoe finishing jack comprising a leg portion and a removable foot portion, means to join them together consisting in a compressible spring pin, means to prevent the 85 turning of the foot portion on said leg portion comprising a lever pivoted to the leg portion and projecting into the foot portion arranged to engage the heel of the shoe to stretch the same rearwardly, and operating devices 90 therefor.

3. A shoe finishing jack comprising a leg portion and a removable foot portion, uniting devices therefor comprising a pin and a lever, said lever engaging both said leg and 95 foot portions on both sides of said lever and arranged to engage the heel of the shoe to stretch the same rearwardly, and operating devices for said lever.

In testimony whereof I affix my signature, 100 in presence of two witnesses.

GEORGE HENRY CLARK.
